US00D827684S

(12) **United States Design Patent** (10) Patent No.: **US D827,684 S**
 Wilson et al. (45) Date of Patent: ** Sep. 4, 2018

- (54) **MULTIPLE SPINNER CAROUSEL FOR DRESSING A GRINDING WHEEL**
- (71) Applicant: **1339513 Ontario Ltd.**, Harrow (CA)
- (72) Inventors: **Murray David Wilson**, Harrow (CA); **Steven David Wilson**, Harrow (CA); **Omer Leon Hageniers**, Windsor (CA)
- (73) Assignee: **1339513 ONTARIO LTD.**, Harrow (CA)
- (**) Term: **15 Years**
- (21) Appl. No.: **29/557,907**
- (22) Filed: **Mar. 14, 2016**

Related U.S. Application Data

- (60) Continuation of application No. 29/486,521, filed on Mar. 31, 2014, now Pat. No. Des. 751,614, which is a division of application No. 29/453,378, filed on Apr. 29, 2013, now Pat. No. Des. 701,890, which is a continuation of application No. 29/428,491, filed on Jul. 31, 2012, now Pat. No. Des. 681,077, which is a continuation of application No. 29/388,322, filed on Mar. 28, 2011, now Pat. No. Des. 665,830.

(57) **CLAIM**

The ornamental design for a multiple spinner carousel for dressing a grinding wheel, as shown and described.

DESCRIPTION

FIG. 1 is a perspective view of a multiple spinner carousel in accordance with the present teachings.

FIG. 2 is an opposite view of FIG. 1.

FIG. 3 is a top view of the multiple spinner carousel of FIG. 1.

FIG. 4 is a bottom view of the multiple spinner carousel of FIG. 1.

FIG. 5 is a front view of the multiple spinner carousel of FIG. 1.

FIG. 6 is a rear view of the multiple spinner carousel of FIG. 1.

FIG. 7 is a side view of the multiple spinner carousel of FIG. 1.

FIG. 8 is an opposite view of FIG. 7.

FIG. 9 is a perspective view of the multiple spinner carousel of FIG. 1 attached to a grinding machine adjacent a grinding wheel in accordance with the present teachings.

FIG. 10 is a perspective view of the multiple spinner carousel of FIG. 1 without the broken line showing of environmental structure.

FIG. 11 is an opposite view of FIG. 10.

FIG. 12 is a top view of the multiple spinner carousel of FIG. 10.

FIG. 13 is a bottom view of the multiple spinner carousel of FIG. 10.

FIG. 14 is a front view of the multiple spinner carousel of FIG. 10.

FIG. 15 is a rear view of the multiple spinner carousel of FIG. 10.

The broken line showing of portions of a multiple spinner carousel for dressing a grinding wheel is included for the purpose of illustrating environmental structure and forms no part of the claimed design.
